United States Patent Office.

PHILIP HIGDON, OF LEWISPORT, KENTUCKY.

Letters Patent No. 94,110, dated August 24, 1869.

IMPROVEMENT IN BALING-PRESSES.

The Schedule referred to in these Letters Patent and making part of the same.

To all whom it may concern:

Be it known that I, PHILIP HIGDON, of Lewisport, in the county of Hancock, and State of Kentucky, have invented a new and useful Percussion Baling-Apparatus, for hay, cotton, &c.; and I do hereby declare that the following is a sufficiently full, clear, and exact description thereof, to enable any one skilled in the art to which my invention appertains, to make and use it, reference being had to the accompanying drawings, which form part of this specification.

My apparatus is provided with a "press-box," which may be constructed in any common or suitable manner.

The follower, by which the compression of the hay, cotton, or other material, is performed, may be constructed like the follower of a press.

But my apparatus differs from a common press, in that the compression of the material is effected by percussion from the follower itself, which, for this purpose, is made quite heavy, and, in operation, is repeatedly raised to such a height that, in falling, it will so crush and pack the hay, cotton, or other material, as in a great measure to destroy or overcome its resilience.

In operation, the press-box is first filled with loose hay or cotton, and then closed. The follower is then allowed to fall, crushing the material into small compass within the box. The follower is then raised, and as it approaches its highest position, an additional quantity of material is introduced, when the follower falls again; and this operation is repeated until a sufficient quantity of material has been introduced to form a bale, by which time the whole material will, by the successive strokes of the follower, be crushed and compressed more permanently and effectually, and with much less labor, than with screw or lever-presses of common construction.

In the drawings—

Figure 1 is a perspective view of my improved apparatus.

Figure 2 represents a vertical section of the same, in the plane indicated by the line $x\ x$, figs. 3 and 4.

Figure 3 represents a horizontal section, at $y\ y$, fig. 2.

Figure 4 represents a horizontal section, at $z\ z$, fig. 2.

Like letters of reference indicate corresponding parts in the several views.

The "press-box" may be constructed with a permanent end, A, a yielding end, B, and two doors, C C.

The doors are hinged at $c\ c$, and secured at their free ends by catches D D, which are hinged to the end B of the box.

While the bale is being formed, the free end B is held up to its work by a hinged bar, E, secured at its upper end by a catch, e.

The follower F is attached to, or forms the lower part of a gate, G, which works in vertical guide-ways H H, and is furnished with a rack, g, for the purpose of elevating the follower, by means of a pinion, I, the shaft J of which is mounted at its inner end (near which the pinion is placed) in a slide, K, which is furnished with a spring-catch, L, for the purpose of holding the pinion I in gear with the rack g when the follower is to be raised.

When the catch L is released, a spring, M, holds the pinion out of gear with the rack.

The pinion-shaft may be rotated by arms, or by a hand-wheel, N, or by an endless cord, or any other suitable means.

A pawl, P, engaging in a ratchet-wheel, R, prevents the shaft J turning backward, and thus supports the follower at any height until the latter reaches the upper extremity of its stroke, when it strikes a projection, f, upon the catch L, so as to elevate the said catch, and permit the projecting and toothless part g' of the rack to throw the pinion I out of gear. The follower then descends instantaneously, and with great force, on the material within the box.

S represent the upper doors, which are opened to receive the hay or other material to be pressed.

They are supported, when open, upon brackets T, and may be held shut by rods U, resting upon said brackets.

In operation, the follower is first raised nearly to its highest point, and there allowed to rest, while the press-box is completely filled with loose hay or other material.

The doors S are then closed, and the follower is run up until the tripping-mechanism releases the rack g from the pinion I, when the follower descends with violence upon the hay, and crushes and compresses it within the box.

The follower is then raised again, by drawing the pinion into gear with the rack, by means of a cord, k, a further quantity of hay is introduced, and the follower again allowed to descend.

This operation is repeated until a sufficient quantity of hay or other material has been introduced to form a bale, that first placed in the box receiving the effect of all the successive blows which are made.

A smaller quantity of hay is introduced after each successive stroke, and by the time the bale is completed, the whole body becomes very compact and solid.

When the bale is to be hooped and removed, the unhitching of the catch e releases the yielding end B of the box, and the doors C C are thrown open for hooping the bale, while the follower still rests upon it; or the parts may be arranged so that the doors C C can be opened for hooping before the yielding end B of the box releases the bale.

The above-described apparatus is of very cheap construction, in comparison with its efficiency. It is also very convenient in use, because the bale is formed at about the level of the floor, instead of at a considerable height above the floor, as is the case with many presses in use.

Having thus described my invention,

What I claim as new, and desire to secure by Letters Patent, is—

1. In the described combination with a "press-box," A B C C, elevating-mechanism *g* I J, and a suitable

tripping-device, the percussion follower F G, constructed and arranged to operate as herein represented and described, for the purpose set forth.

2. The tripping-mechanism K L f, operating, in combination with the follower F, pinion I, and rack *g*, substantially as described.

P. HIGDON.
